UNITED STATES PATENT OFFICE.

FRED G. MAYER, OF MYSTIC, SOUTH DAKOTA, ASSIGNOR OF ONE-HALF TO HUGH McLELLAN,
OF MYSTIC, SOUTH DAKOTA.

CAN-OPENER.

No. 922,932.

Specification of Letters Patent.

Patented May 25, 1909.

Application filed December 12, 1908. Serial No. 467,300.

To all whom it may concern:

Be it known that I, FRED G. MAYER, a citizen of the United States, residing at Mystic, in the county of Pennington and State of South Dakota, have invented new and useful improvements in Can-Openers, of which the following is a specification.

This invention relates to can opening machines and the object of the invention is to provide a device of this character which may be readily adjusted to any size can, and which when positioned upon the machine will be effectively retained thereon without the necessity of holding the same while the top or lid is being removed.

With the above and other objects in view which will be more apparent as the description progresses the invention resides in the novel construction and combination of elements hereinafter fully described and claimed.

In the accompanying drawings there has been illustrated a simple and preferred embodiment of the invention, and in which:

25 Figure 1 is a side elevation of a machine constructed in accordance with the present invention. Fig. 2 is a central vertical longitudinal sectional view of the same. Fig. 3 is an elevation upon the line 3—3 of Fig. 1 looking in the direction of the arrows. Fig. 4 is a transverse sectional view upon the line 4—4 of Fig. 1. Fig. 5 is a detail sectional view taken upon the line 5—5 of Fig. 1. Fig. 6 is a detail view of the knife or cutting 35 element.

In the drawings the numeral 1 designates the base of the machine. This base 1 is provided with a plurality of spaced ears 2 having suitable vertical openings adapted for 40 the reception of securing elements by which the machine is attached to a table or like support. The body of the machine is of a preferably circular formation and has its upper face provided with a plurality of 45 spaced notches or teeth 3 adapted to provide means for securely retaining a can to be opened upon the base in a manner hereinafter to be described.

The circular base 1 is provided with an integrally formed offset portion 4 from which extends vertically a standard 5. This

standard 5 is preferably rectangular in cross-section and has one of its faces provided with incut teeth designated by the numeral 6 and clearly illustrated in Figs. 1 and 4 of 5 the drawings.

The numeral 7 designates the slidable supporting arm of the machine. This arm 7 is provided with a rectangular opening upon its enlarged or headed portion 9, and the opening 8 is adapted for the reception of the rectangular standard 5. The head 9 is provided upon one of its faces with outstanding ears 10, suitably spaced apart and adapted for the reception of a pivoted lever 11. The spaced ears 10 are of a distance apart approximately equalling the width of the teeth 6 provided upon the standard 5, and that portion of the head 9 between the said ears is cut away for a suitable distance so as to provide an opening communicating with the teeth of the standard 5.

The lever 11 is provided with a headed portion 12 which has its face provided with outwardly projecting teeth 13, adapted to engage the teeth 6 when the lever is swung upon its pivot. By reference to Fig. 4 of the drawings it will be noted that the pivot 14 of the lever 11 is pivoted eccentrically of the head 12, so that when the lever is swung 80 at an angle in either direction the teeth 13 will be brought out of contact with the teeth 6, thereby allowing the head 9 to be moved upon the standard 5 in either direction.

The opposite end of the arm 7 is provided 85 with a tubular socket member 15 which is adapted for the reception of a cylindrical rod 16 having its upper extremity provided with an offset handle 17. The member 16 is retained in position upon the tubular head 15 through the medium of a suitable offset or collar 18, and has its lower portion extending a suitable distance below the tubular member.

The numeral 19 designates the head of the 95 machine. This head 19 comprises an outer annular ring 20 having a plurality of spaced arms or spokes 21 radiating to a central hub 22. This hub 22 is provided with a suitable opening 23 adapted for the reception of the 100 extending portion of the rod or spindle 16 and the spindle and hub are securely locked

together through the medium of a suitable pin 24 engaging alining openings in the wall of the hub and the spindle. One of the radiating spokes designated by the numeral 25 is preferably rectangular in cross section and is provided with a longitudinal groove or opening terminating a suitable distance away from the connection of the hub with the spindle 16. This opening comprises a 5 cylindrical upper portion or bore 26 having a reduced portion 27 communicating with the lower face of the spoke provided within the bore and establishing a communication with the bore from the lower face of the 10 spoke. The reduced opening 27 has both of its longitudinally extending walls arranged in a substantially vertical plane, and one of these walls is smooth while the opposite wall is provided with vertically arranged spaced 15 teeth 28.

The numeral 29 indicates the cutting element or knife. This knife 29 is provided with a head portion 30 of a cross sectional contour corresponding with and of a size approximately equaling or slightly lesser than 25 the walls provided by the bore 26. The head 30 is provided with a reduced downwardly extending portion 31 having a centrally arranged tooth 32 and provided with a knife or 30 cutting element 33. The reduced portion 31 is of a lesser thickness than the width between the vertical walls of the opening 27 so that the head 30 may be rotated in the bore 26 to bring the tooth 32 into or out of engagement with the teeth 28 of the arm 25. By this arrangement it will be noted that the cutting member 29 may be positioned at any desired point along the arm 25 so as to provide for the various widths of cans to be 35 opened by the machine. The spindle 16 has its lower portion projecting below the head 19 reduced and pointed so as to provide a means for pivotally engaging the can while the cutting element 29 is operated.

40 Trunnioned between the radiating arms 21 and the arm 25 are the rollers 34. These rollers 34 are adapted to extend below the undersurface of the head 19 and are adapted to provide a bearing for the head as it is rotated around the can which is to be opened.

45 The operation of the device is as follows: The lever 11 is swung to a suitable angle upon its pivot 14 so as to release the teeth 13 from the teeth 6 of the standard 5. The 50 head is raised a sufficient distance away from the base 1 and a can is positioned upon the base. The head 19 is then brought slowly downward until the pointed extension 35 of the spindle 16 is positioned central 55 of the head of the can. The lever 11 is then swung upon its pivot 14 causing the teeth 13 of the said lever to engage the teeth 6 of the track 5 and effectively force the head down-

ward in the direction of the can and the point 35 and the cutting element 33 within 60 the head of the can. The handle 17 is then rotated and the top or cap removed from the can.

65 By providing an adjustable knife as described, it will be apparent that the device should be rotated in only one direction so the teeth 3 arranged upon the base 1 are beveled in a direction opposite to that in which the head is rotated, thus the teeth provide an effective bearing upon the lower 75 face of the can and prevent movement thereof in any direction.

70 While I have illustrated and described the preferred embodiment of the machine, as it now appears to me, it is to be understood that minor details of construction within the 80 scope of the invention may be resorted to if desired.

Having thus fully described the invention 85 what is claimed as new is:

1. In a device for the purpose set forth, a circular base having its entire upper face provided with a plurality of notches arranged in series, a rotary head vertically adjustable in relation to the said base, said head having a 90 bore provided with notches, and a removable cutting member adapted to be positioned within the bore and to engage the notches.

2. In a machine for the purpose set forth, a cylindrical base provided with notched 95 teeth arranged in series, a vertical arm upon the base having inset teeth, a head supporting member slidably mounted upon the arm of the base, an eccentrically pivoted toothed lever upon the support, spaced rollers upon 100 the head, said head having a longitudinally extending bore provided with teeth upon one of its sides, and a cutting element having an enlarged head and an offset tooth adapted to be slidably positioned within the bore of the 105 head, substantially as and for the purpose set forth.

3. In a machine for the purpose set forth, a base provided with teeth, a vertical standard projecting from said base, teeth upon one 110 side of the standard, a head supporting member slidably mounted upon the standard, ears upon one face of the sliding member, the said face having a cut away portion between the ears communicating with the teeth 115 of the standard, a lever having an enlarged head having one of its faces provided with teeth eccentrically pivoted between the ears, a rotatable head connected with a spindle upon the supporting member, a handle for 120 the spindle, the head comprising an outer ring having radiating arms, rollers between the arms, one of said arms having a longitudinally extending bore provided with a reduced portion having vertical walls, one of 125 said walls being provided with teeth, a cut-

ting element, said element comprising a head portion of a cross sectional contour similar to that of the bore, a reduced extending portion of a lesser width than the vertical walls 5 of the bore, a tooth upon this reduced portion adapted to contact with the teeth of one of the vertical walls, a knife blade extending from this reduced portion, and a centrally

arranged downwardly projecting sharpened member for the rotary head.

In testimony whereof I affix my signature in presence of two witnesses.

FRED G. MAYER.
